(57) **CLAIM**

The ornamental design for a guitar body, as shown and described.

DESCRIPTION

FIG. 1 is a perspective view of a guitar body showing my new design;

FIG. 2 is a front plan view thereof;

FIG. 3 is a left side elevation view thereof;

FIG. 4 is a bottom elevation view thereof;

FIG. 5 is a right side elevation view thereof;

FIG. 6 is a back plan view thereof; and,

FIG. 7 is a top elevation view thereof.

The broken lines shown in the figures illustrate the environment only and do not form part of the claimed design.
